Louis Henri Sibert Bellem INVENTOR

BY C. P. Soepel

ATTORNEY

UNITED STATES PATENT OFFICE.

LOUIS HENRI LIBERT BELLEM, OF NEUILLY-SUR-SEINE, FRANCE.

ATOMIZER.

Application filed December 13, 1922. Serial No. 606,761.

To all whom it may concern:

Be it known that I, LOUIS HENRI LIBERT BELLEM, a citizen of the Republic of France, and resident of Neuilly-sur-Seine, France 5 (post-office address 5 Rue du Lieutenant Boncour), have invented a new and useful Atomizer, which improvements are fully set forth in the following specification.

The object of my invention is to provide 10 an atomizer device designed to feed with liquid fuel four cycle explosive engines, in which the first cycle or stroke causes a vacuum, as those of the Bellem et Bregeras type.

15 My atomizer is intended to be intercalated between the engine and a distributor pump of the type described in the application filed in France for the Bellem et Bregeras patent.

20 In order to make my invention more clearly understood I have illustrated, as an example, a practical embodiment thereof in and by the appended drawing herein.

25 Figure 1 is a longitudinal section of an atomizer constructed according to my invention.

Figure 2 is a cross section according to line $x-x$ of the grooved cylinder secured in the hollow stemmed valve.

30 My atomizer is essentially constituted by a valve fitted with a hollow stem 1 in which is secured, by a cross pin 2, a cylinder 3 provided with grooves 4 arranged on any suitable manner, as for instance according to the generating liner or helicoidally.

35 Said grooves are interrupted from place to place by circular recesses 5. The pin that holds cylinder 3 in place cannot become displaced since held in position by cross piece 6.

40 Hollow valve 1 is closed at its lower part by a plug 7 in which are cut grooves 8 the number and size of which depend on the quantity of fuel to be atomized.

45 Said part is secured on the valve and its grooves 8 correspond to holes 9 bored in the valve at right angles to the grooves.

In line with those grooves 8, holes 10, inclined therefore 45° like the valve seat, are bored through the wall of hollow valve stem 1.

50 The lower grooves of part 3 are located just opposite holes 10, it being understood that there are as many holes 10 as grooves 4.

At its upper part, member 3 has also grooves which are more or less long and

wide according as there is more or less fuel 55 to be atomized.

In recess 5 located immediately under said grooves holes 11 open out bored at 45° through the hollow valve stem. Said holes receive air coming from holes 12 of cross 60 piece 6 and grooves 13 of guide 14. Cross piece 6 is provided at its lower part with grooves 15 and block piece 16 against the conical head of the hollow valve. Said piece 16 has grooves 17 and is dog-secured on the 65 valve cone so that holes 9 open on grooves 17.

Members 6, 14 and 16 are blocked on the valve by a split nut 18 screwing on the upper threaded end of the hollow valve stem 70 and prevented from untightening by a set screw 19.

The foregoing parts are therefore mounted, as shown by Figure 1, on the engine valve buffers 20 or at any other preferred 75 place.

A spring 21 returns the valve to its seat 22.

A cap 23 screwing on body 20 is provided with holes 24 permitting air to enter chamber 25. A damper 25' is adapted to be operated on starting so as to close holes 24 80 and create a depression that will suck in fuel through pipe 26 independently of any other feeding device, feeding being effectuated mechanically during operation. 85

The same result would be obtained by omitting damper 25' and arranging around tube 26 a solid washer working freely on said tube and resting through gravity on the top of the hollow valve. On starting, the vacuum created by engine suction in the hollow valve closed by the said washer would produce a fuel intake, and once under way, fuel would be pump delivered. 90

Operation is as follows. The atomizer is 95 mounted on an engine the air valve of which opens only about the end of travel, on the piston's downstroke, the atomizer being automatic, opens and its valve assumes the position shown by Figure 1. At this moment 100 fuel is fed to the atomizer by a suitable adjustable delivery pump connected with the atomizer by a conduit. Air emulsified fuel then passes into the upper grooves. Flow through these is effectuated under weak depression since there is an air intake through holes 11. This is intended to permit the 105 quantity of fuel required for an explosion

to be stored in the upper grooves, said quantity being kept up by capillarity and exhausting at one flow when the atomizer valve opens since air holes 11 prevent a sudden suction of fuel.

As soon as fuel and air have gone beyond first recess 5 the air and fuel emulsion circulates in the baffle arranged grooves until, through the lower grooves of member 3 a violent air-blast coming from holes 10 continues the atomization already taking place in vacuum space 28. Produced fuel sprays issue through holes 9 and are violently shattered by a very fast air blast rushing through grooves 17 of member 16 and coming under the depression produced by the piston's downstroke. As is well known, sprays being produced in vacuum are most minutely atomized, resembling mist or smoke.

It should be plainly understood that my atomizer as above described is given, only as an example and that I reserve every right to make any constructional modifications without departing from the scope of my invention.

Having now particularly described and ascertained the nature of my said invention as well as the manner in which the same is to be performed, I declare that what I claim is:

1. An atomizer for feeding four cycle explosion engines, creating a vacuum on the first cycle or stroke; such atomizer being constituted by a hollow-stemmed conical-headed valve, the stem and head of which are holed with suitable air inlets; a grooved plug secured on the lower end of the valve

and the grooves of which are opposite the valve head apertures; a cylinder provided with grooves and recesses and located inside the hollow stem; two successive jackets surrounding the hollow stem and provided with air passage grooves, a grooved guide blocking said jackets on the valve head; a nut screwing on the upper portion of the hollow stem and compacting the whole as unit; a body secured to the engine and within which said unit slides; an antagonistic spring keeping the valve on the latter's seat; and a cap having air inlet holes adapted to be closed by a damper.

2. An atomizer for feeding four cycle explosion engines, creating a vacuum on the first cycle, or stroke, comprising a hollow stemmed conical-headed valve, the head and stem of which are provided with suitable air inlets; a plug secured in the lower end of the valve and provided with grooves registering with the valve head air inlets, a cylinder located within said hollow stem provided with a plurality of grooves parallel to its generating line and alternating with annular grooves, jackets surrounding the hollow stem and provided with air passage grooves, a body adapted to be secured to an engine, and means connected with said members and said body adapting said members to operate as a unit within said body.

In testimony whereof I have signed this specification in the presence of a subscribing witness.

LOUIS HENRI LIBERT BELLEM.
Witness:
CHARLES LEÓN LOISE.
